UNITED STATES PATENT OFFICE.

WILLY MOEBIUS, OF HANOVER, GERMANY.

CUTTING DEVICE FOR CLAY-PRESSES.

SPECIFICATION forming part of Letters Patent No. 670,289, dated March 19, 1901.

Application filed February 10, 1900. Serial No. 4,766. (No model.)

To all whom it may concern:

Be it known that I, WILLY MOEBIUS, a subject of the Emperor of Germany, residing at Hanover, in the Empire of Germany, have invented a certain new and useful Cutting Device for Clay-Presses, of which the following is a specification, reference being had therein to the accompanying drawings.

A great variety of cutting devices is known in the pipe and brick making industry, and most of them use wires as the cutting agent. However, I have found none of them to prove satisfactory when producing drain or other pipes nested together by the use of my process as described by me in an application for Letters Patent filed and executed on the same day and date as this present application. Owing to the peculiar manner in which the pipes are produced here in concentric strings nested together, it becomes a matter of the utmost importance to execute the cutting of the string in the desired length in a very exact and careful manner. To obtain smooth surfaces and straight cuts, the cutting device must move together with the string of pipe, and the cutting motion must be very rapid and effective. Another important factor which has to be considered is the experience that the different concentric pipes of the string do not move with the same speed, and though this difference is only small it would cause the different pieces of pipe nested together to be of varying and various length. Care must therefore be taken to use a device which will cut off a sufficient length of the string as waste to be sure that the pieces cut for use are of equal length. These considerations have led to the construction of my device as illustrated in the accompanying drawings, in which—

Figure I shows a side elevation of the mouth-piece of a clay-press as used in my process, together with a view of the cutting device. Fig. II shows the same as seen from above.

Similar letters mark similar parts.

P is the mouthpiece of a clay-press, and A the face-plate of the same, carrying the central cone G and the concentric knives M M', bolted to it by means of the cross-bar CB and bolts p p'.

R R' R² are the nested pipes; Z, a guide-roller supporting same; SR², a set of the nested pipes cut to the required length by the cut-

ting-frame S by means of the cutting-wires D D'; B, a carrier on which the cut pipes are removed to the drying-house, and W a carriage running with the wheels V V' on the rail T.

K is the stop to upset the cutting-frame, and F the spring operating the same.

h h' are hooks holding the cutting-frame set in position for cutting by engaging projections d d'.

E is the waste; U, a support for the string of pipe; H, handles by which the carrier is to be lifted from the carriage, and O the conical and circular orifice of the face-plate A of the mouthpiece P.

The operation of the device proceeds as follows: The string of nested pipes emerging from the mouth of the press passes over the guide-roller Z and the semicircular support U onto the carrier B until it reaches K, which, giving way before the pressure, takes the carriage W along until the hooks h h' release the projections d d', and with them the cutting-frame S, with its cutting-wires D D', which had been held below B. The cutting-frame S, which is pivoted on both ends in the uprights N N', bolted to the back of the carriage W, is now suddenly projected upward by the action of spring F, causing the cutting-wires to be drawn through the string and cutting it in the desired length. The carrier is now quickly removed by one laborer, while another resets the cutting-frame and places another carrier on the carriage, when the operation is repeated, and so on. When pipes of a smaller diameter are to be produced, which can easily be removed by hand, the carrier may be replaced by guide-rollers provided with semicircular grooves corresponding to the diameter of the string. In this case the cutting-frame need not be operated by a spring, but may be moved up and down by hand, cutting the string in each up or down movement, care being taken, however, always to move the carriage back to its original position to allow the cutting of the moving string. The waste ends E of the pipe-string R², which are dropped to the ground by the upsetting of K, are collected from time to time and returned to the feeder of the press.

Having thus fully described my invention, what I claim as new, and desire to secure by Letters Patent, is—

In a cutting device for clay-presses the combination of a carriage, movable on rails, with a cutting-frame, provided with cutting-wires and actuated by a spring, adapted to be set 5 and held in position by suitable hooks and projections engaging each other, and a stop to carry along the carriage and to thus disengage the hooks and projections and release

the spring-actuated cutting-frame, for the purpose as set forth and described.

In testimony whereof I affix my signature in presence of two witnesses.

WILLY MOEBIUS.
